(57) **CLAIM**

I claim the ornamental design for a fecal loop, as shown and described.

DESCRIPTION

FIG. 1 is a perspective view of a fecal loop showing my new design;

FIG. 2 is a top view thereof;

FIG. 3 is a bottom view thereof;

FIG. 4 is a right elevation view thereof;

FIG. 5 is a left elevation view thereof;

FIG. 6 is a front view thereof; and,

FIG. 7 is a rear view thereof.
